Attorney

Inventor

Joseph B. Weeks

UNITED STATES PATENT OFFICE.

JOSEPH BENJIMAN WEEKS, OF NORTH SYDNEY, NOVA SCOTIA, CANADA.

GAUGE FOR BOILER TUBES.

Application filed October 20, 1921. Serial No. 509,138.

To all whom it may concern:

Be it known that I, JOSEPH B. WEEKS, a subject of the King of Great Britain, residing at North Sydney, Province of Nova Scotia, Canada, have invented certain new and useful Improvements in Gauges for Boiler Tubes; and I do hereby declare that the following is a full, clear, and exact description of the invention, such as will enable others skilled in the art to which it appertains to make and use the same.

The present invention relates to new and useful improvements in gauges for boiler tubes.

15 The primary object of the invention is the provision of a gauge for boiler tubes which will regulate the distance they protrude through the boiler sheet when riveting the same in position.

20 Another object of the invention is the provision of a gauge such as above referred to which can be adjusted so that the boiler tubes will project through the sheet a desired degree in order that they can be properly riveted in position.

A still further object of the invention is the provision of means for gripping the tube when holding the same in position to prevent its turning.

30 A still further object of the invention is the provision of a device such as above referred to, which will be comparatively simple and inexpensive to manufacture, reliable and efficient in use, and readily operated.

35 With the above and other objects in view, the present invention resides in the novel features of construction, formations, combinations and arrangements of parts to be hereinafter more fully described, claimed, and illustrated in the accompanying drawing forming a part of the present application, and in which;

Figure 1 is a perspective view of the device;

45 Fig. 2 is a side view of the same positioned within the boiler tube;

Fig. 3 is an enlarged longitudinal sectional view taken through the central portion of the device;

50 Fig. 4 is a sectional view taken transversely through the central portion thereof; and,

Fig. 5 is a perspective view of the gripping member removed.

55 Referring now to the accompanying draw-

ing by corresponding characters of reference throughout the several views, the numeral 10 designates in general an ordinary boiler tube while 11 is a tube sheet. My improved gauge is shown at 12 and consists of a tapered body portion 13 having a shoulder 14 formed intermediate the ends thereof and a handle 15 provided at the outer end.

The shoulder portion 14 and adjacent end of the tapered body 13 are provided with a longitudinal recess 16 the inner end of which is enlarged to form a T-extension 17 and in this recess 16 a locking device 18 is mounted. The locking device 18 comprises a handle portion 19 and a cross head 20 provided with a serrated surface 21. This member is pivoted as at 22 within the recess 16 and the head 20 is forced inwardly to retracted position by the spring 23. A sleeve 24 is slidably mounted on the shoulder 14 being retained in position by the set screws 25 which can be adjusted to and from the ends of the shoulder to permit the proper protrusion of the tube 10 beyond the outer wall of the sheet 11.

In use, the sleeve 24 is set to the desired position and the tapered body portion 13 inserted into the end of the tube, the protruding end thereof extending through the sleeve 24. The tube is then forced until the end of the sleeve engages the outer face of the sheet 11 and the gripping member 20 is then forced into engagement with the inner side of the tube 10 which prevents the tube from turning while the opposite end thereof is being riveted in position.

From the foregoing description, taken in connection with the accompanying drawing, it will be manifest that a gauge for boiler tubes is provided which will fulfill all of the necessary requirements of such a device, and it should be understood in this connection that various minor changes in the specific details of construction can be resorted to within the scope of the appended claims, without departing from the spirit or sacrificing any of the advantages of the invention.

Having thus fully described the invention, what I claim as new and desire to protect by Letters Patent is:—

1. The herein described apparatus comprising a tapered body portion having a handle formed at one end thereof, a shoulder formed upon said body portion, a sleeve sur-

rounding said shoulder, a lever pivoted to said body, and a gripping device at one end of said lever for engaging a boiler tube.

2. The herein described apparatus comprising a tapered body portion having a handle formed at one end thereof, a shoulder formed upon said body portion, a sleeve adjustable upon said shoulder and a gripping device for engaging a boiler tube.

10 3. The herein described apparatus comprising a tapered body portion, a handle formed at one end thereof, a shoulder interposed between the body portion and the handle, a sleeve adjustable upon said shoulder, said body portion having a groove therein, a locking device mounted in said groove, and means for forcing the locking device outwardly from the tapered body portion, substantially as and for the purposes set forth.

20 4. The herein described apparatus comprising a tapered body portion, a shoulder formed thereon, a handle projecting from the body portion, a sleeve adjustable upon said shoulder, set screws carried by the

sleeve for engagement with the shoulder, said body portion having a slot therein, a gripping member pivoted in the slot, and a handle extending from the gripping member for forcing the gripping member outwardly, as and for the purposes set forth.

25 5. The herein described apparatus comprising a tapered body portion, a slot provided in said body portion and having one end enlarged forming a T, a gripping member having a serrated T-head provided in the slot, a shoulder formed upon the body portion, a sleeve slideable upon said shoulder for adjustment, set screws passing through the sleeve and engaging the shoulder for locking the sleeve in position, a handle formed upon the gripping member for forcing the latter outwardly, and a spring interposed between the handle of the gripping member and the handle of the apparatus for forcing the gripping member to inoperative position.

In witness whereof I have hereunto set my hand.

JOSEPH BENJIMAN WEEKS.
